G. L. MURPHY,
EXTENSION SWINGING STACKER,
APPLICATION FILED OCT. 11, 1919.

Patented Nov. 1, 1921.

2 SHEETS—SHEET 2.

This technical drawing illustrates a mechanical assembly, possibly a clutch or transmission component. The drawing shows a central shaft with various gears and a lever system. Key labeled parts include:

- 12: A lever or handle at the bottom.
- 13: A housing or frame.
- 15: A gear or sprocket.
- 16: A lever or handle on the left.
- 17: A lever or handle on the right.
- 18: A lever or handle at the top left.
- 19: A lever or handle at the top right.
- 23: A housing or frame at the top.
- 52: A lever or handle on the left side.
- 53: A lever or handle on the right side.
- 56: A lever or handle at the bottom center.
- 57: A gear or sprocket.
- 58: A gear or sprocket.
- 59: A gear or sprocket.
- 60: A lever or handle.
- 61: A lever or handle.
- 62: A gear or sprocket.
- 63: A lever or handle.
- A3: A small part at the bottom center.
- 12: A lever or handle at the bottom right.

UNITED STATES PATENT OFFICE.

GEORGE L. MURPHY, OF HAYDEN, COLORADO.

EXTENSION SWINGING STACKER.

1,395,512.

Specification of Letters Patent.

Patented Nov. 1, 1921.

Application filed October 11, 1919. Serial No. 330,132.

To all whom it may concern:

Be it known that I, GEORGE L. MURPHY, a citizen of the United States, residing at Hayden, in the county of Routt, State of Colorado, have invented certain new and useful Improvements in Extension Swinging Stackers; and I do hereby declare the following to be a full, clear, and exact description of the invention, such as will enable others skilled in the art to which it appertains to make and use the same.

This invention relates to stacking machines and it has for its object to provide a construction for the stacking of hay, straw or similar material, with which the stack may be built very low or of extreme height or may be built of varying heights, as desired. A further object of the invention is to provide a construction that will permit of the building of a stack of extreme length when desired or of shorter length when required and in which furthermore there may be practised extreme economy in labor. Thus, while stacks of little height and short length may be built with this apparatus, both dimensions may be increased as desired, materially beyond what is usual and with great saving in labor.

In the drawings:

30 Figure 1 is a perspective view showing a stacker embodying the present invention, the stacker arms being raised and extended, ready to discharge the load onto the stack.

Fig. 2 is a sectional view taken longitudinally through one of the extensible stacker arms, showing the arrangement of the cable for extending the arms as they are raised, the view showing also the plurality of hitched links that are attached to the cable for determining the degree of extension of the arms in operation.

Fig. 3 is a plan view of the rock shaft that carries the stacker arms, together with the associated gearing through the medium of which the stacker is swung laterally and automatically as raised, together with the shifting mechanism for throwing the gearing into and out of operation.

Fig. 4 is a longitudinal section through the bottom frame and the parts directly supported by it, the section including also the arc-shaped rack.

Referring now to the drawings, the present construction comprises a bottom frame including the sills 10 and 11 that are con-

nected at their forward ends by the cross beam 12 and near their rear ends, by the cross beam 13, the sills being mounted upon a platform 14 that is provided with skids or wheels as preferred, to facilitate its 60 transportation.

Upon the rear end portions of the sills, adjacent to and in advance of the beam 13, are the bearing blocks 15 in which are mounted the trunnioned ends 16 of a cross sectionally angular rock shaft 17. Fixed to the ends of the shaft 17 beyond the said bearings, are the socket members 18, each consisting of a plate bent upon itself and perforated to receive the corresponding end 70 of the shaft, beyond which to their free ends, the end portions of the plate diverge. Between these divergent portions are received and bolted the correspondingly shaped lower ends of the inner sections 19 75 of the stacker arms. In what are the upper edges of the arm sections 19 when they are in reclining positions, are formed longitudinal channels 20 that extend through their outer ends which latter are slotted vertically to receive the pulley wheels 21 that are rotatably mounted therein and provided with U-shaped keeper plates 22, the ends of which are confined between the corresponding pulleys and the side walls of the 85

Upon the channeled edges of the arm sections 19, are slidably disposed the outer arm sections 23 and passed over each pulley wheel 21 and through the corresponding channel 20 is a cable 24, that is attached to the lower end of the corresponding arm section 23. The other ends of the cables are each provided with a series of hitch links 25 that may be interchangeably en-

gaged with corresponding hooks at the forward ends of the sills 10 and 11. When the arm sections 19 are raised with the rock shaft 17 as a pivot, the arm sections 23 rest upon the sections 19 without longitudinal movement, so long as there is slack in the cables between the pulley wheels 21 and the hooks 26. After the slack has been taken up, however, further upward movement of the arm sections 19 draws upon the cables 105 with the result that the arm sections 23 are advanced along the sections 19, as will be understood. Upon the sections 23 and connecting their forward ends, is mounted the stacker head 27 of usual construction and 110

it will be further understood that the elevation reached by the stacker head before it is dumped, may be determined by the amount of slack initially in the cables, the 5 proper hitch link being engaged with each hook, to correspond with the amount of slack desired.

In order to confine the arm sections 23 slidably upon the corresponding sections 19, 10 U-shaped keeper plates 28 are engaged over the sections 23 and are bolted with their sides against the sections 19 so that the sections 23 may slide therethrough while additional plates 29 are bolted against the sides of the 15 rear end portions of the sections 23 and slidably embracing the sides of the sections 19.

To raise and lower the stacker arms and head with the rock shaft 17 as a pivot, a derrick structure is employed that includes 20 a pair of beams 30 that are pivoted at their lower ends against the inner faces of the sills 10 and 11 respectively, that converge and meet at their upper ends and that are held together at their upper ends by the 25 V-shaped plate 31 that embraces them and from the apex of which plate extends a web 32 that is perforated. In this perforation 33 is engaged a ring 34 to which are connected chains or cables 35 that are provided 30 with rings 36 at their other ends that engage perforations 37 in the upstanding webs 38 that project from the bights of the keeper plates 28, previously described. In the perforation 33 is also engaged a ring 39 to 35 which is connected a block 40 that slidably receives a cable 41 that extends downwardly and rearwardly and divergently from the sides of the block and then through blocks 42 that are mounted at the end portions of 40 a cross beam 43 that is supported by short sills 44 mounted upon the platform 14, the beam 48 being held in spaced relation to and transversely above the rear end portions of the sills 10 and 11.

45 In order that the stacker may be swung with the head laterally to deposit its load at different points of the length of the stack, the cross beam 12 is connected by means of the pivot bolt 50 that is engaged through the 50 pivot plate 51 that has its end portions turned downwardly and then outwardly and secured upon the platform 14. With this arrangement, the rear end of the bottom frame or supporting frame, may be swung 55 laterally which will give to the stacker head an opposite movement when the head is beyond the pivot bolt 50 and will give to the stacker head the same direction of movement but with lesser lineal extent if the head is 60 inwardly of the pivot bolt, it being understood that under some circumstances the latter condition may obtain. To facilitate this swinging movement of the supporting frame, it may be provided with wheels 52 65 engaging tracks 53 on the platform but it

will of course be understood that the provision of such wheels and tracks is entirely optional.

In order to automatically swing the supporting frame as the stacker arms are raised, 70 there is mounted in suitable bearings in the beam 13, a shaft 54 having fixed thereon rearwardly of the beam, a beveled gear 55 that meshes with an arc-shaped rack plate 56 that is, in the construction illustrated, secured 75 within a corresponding cavity in the front face of the beam 48 although it will of course be understood that it may be secured against the under face of the beam, or otherwise as desired. Upon the shaft 54 and forwardly 80 of the beam 13, is fixed a second beveled gear 57 while slidably mounted upon the square central portion of the shaft 17 are the mutually connected beveled gears 58 and 59, having their teeth directed toward each 85 other and which when reciprocated upon the shaft 17, alternately mesh with the gear or pinion 57. To shift the gears 58 and 59, a hand lever 60 is pivoted to a notched segmental plate 61 that is fixed to the rock shaft 90 57 and from which lever to the hub of the gear 59, there extends a shift link 62 that is pivoted to both the lever and hub. A latch 63, pivoted to the lever 60, is movable 95 into and out of engagement with the notches of the segmental plate, which latter are so positioned as when thus engaged, the latch will hold the lever with either gear 58 and 59 or neither gear in mesh with the pinion 57. 100

With the mechanism just described, it will be understood that when the gear 58 meshes with the pinion 57 and the stacker arms rise, the gear or pinion 55, operating upon the rack, will shift the rear end of the supporting frame to the right of one facing the stack while when the gear 59 is engaged with the pinion 57, the supporting frame will be given an opposite movement, with movement of the stacker head above explained. 110

When neither gear 58 and 59 is engaged with the pinion 57, the stacker arms rise and fall without any lateral movement and it will of course be understood that this operation may be effected or that either gear may 115 be thrown into mesh with the pinion to effect lateral movement of the stacker head correspondingly, at any time prior to the limit of upward movement of the arms.

Upward movement of the stacker arms 120 is limited by a cable 64 that is connected at one end with the cross brace 65 that connects the forward end portions of the stacker arm sections or members 19, the other end of the cable being connected with a helical spring 125 66 that is connected in turn to a plate 67 held by the pivot bolt 50.

It will of course be understood that the cable 41 may be drawn either at both ends or at one end by horse power or by mechani- 130

cal power through the medium of any desired instrumentality, to effect raising of the stacker arms.

What is claimed is:

- 5 1. In a stacker, the combination with means for raising a load to be stacked, of means operated by the load raising means for moving the load laterally in either direction.
- 10 2. In a stacker, the combination with pivoted means for raising a load to be stacked, of means operated by the pivoted load raising means, for moving the load laterally in either direction.
- 15 3. In a stacker the combination with a rock shaft having stacker arms having a load carrying head, the arms being laterally movable with the shaft and head, of means for raising and lowering the arms with the shaft.
- 20 20 as a pivot, means for swinging the arms and head laterally and means for connecting the swinging means for operation from the rock shaft.
- 25 4. In a stacker, the combination with a platform of a carrier frame pivoted thereon, a rock shaft mounted in the frame, stacker arms carried by the rock shaft and provided with a stacker head, the arms and head being adapted to rise and fall with the shaft as a pivot, gears carried by the shaft, slidably

thereon and angularly movable therewith, a pinion carried by the frame and with which the gears are interchangeably engageable at opposite sides to reversely rotate the pinion in either direction of movement of the shaft, 35 a rack held against movement with the carrier frame and a second pinion operatively connected with the first pinion and engaged with the latter.

5. A stacker comprising a platform, a carrier frame pivotally mounted upon the platform, stacker arms having a head and pivotally mounted upon the carrier frame, a derrick pivoted to the carrier frame and having connections with the arms, a cable slidably 40 connected with the derrick for swinging the latter to raise and lower the arms, blocks with which the cable is slidably engaged at opposite sides and spaced rearwardly from the derrick, and means operable under the 45 influence of pivotal movement of the stacker arms and manually movable into and out of active position, for pivotally moving the carrier frame.

In testimony whereof, I affix my signature, 55 in the presence of two witnesses.

GEORGE L. MURPHY.
